Maurice D. Block

UNITED STATES PATENT OFFICE.

JOSEPH S. APFEL, OF NEW YORK, N. Y.

DESIGN FOR A BOUDOIR-LAMP.

58,865.

Specification for Design.

Patented Sept. 6, 1921.

Application filed January 29, 1921. Serial No. 441,053. Term of patent 7 years.

To all whom it may concern:

Be it known that I, JOSEPH S. APFEL, a citizen of the United States of America, residing at New York city, county and State of New York, have invented a new, original, and ornamental Design for a Boudoir-Lamp, of which the following is a specification, reference being had to the accompanying drawing, which represents a front elevation of a boudoir lamp embodying my new design.

I claim:—

The ornamental design for a boudoir lamp, as shown.

Signed at New York city, N. Y., this 27 day of January, 1921.

JOSEPH S. APFEL.

Witnesses:

MAURICE BLOCK,
EDUARD A. JARVIS.
